UNITED STATES PATENT OFFICE.

LEE S. BURRIDGE, DECEASED, LATE OF NEW YORK, N. Y., BY FRANCIS O. BURRIDGE,
EXECUTOR, OF NEW YORK, N. Y., ASSIGNOR, BY MESNE ASSIGNMENTS, TO UNDER-
WOOD TYPEWRITER COMPANY, OF NEW YORK, N. Y., A CORPORATION OF DELAWARE.

TYPE-WRITING MACHINE.

1,259,599.

Specification of Letters Patent. Patented Mar. 19, 1918.

Application filed August 6, 1915. Serial No. 43,992.

To all whom it may concern:

Be it known that LEE S. BURRIDGE, deceased, late a citizen of the United States, and late residing in the borough of Manhattan, county, city, and State of New York, invented certain new and useful Improvements in Type-Writing Machines, of which the following is a specification.

This invention relates to the line-spacing mechanism of typewriting machines, and its object is to provide a simple and inexpensive mechanism which shall be of very light weight and extremely compact as well as durable, so as to be suitable for use in typewriters of the portable class.

The platen frame or carriage of the typewriter may be made of sheet metal, and may comprise an end plate, and the line-space mechanism may be compactly mounted upon the inner and outer sides of said end plate; the line-spacing parts being made preferably all of sheet metal and compactly assembled.

The line-space lever may have a finger-piece to coöperate with a finger-piece formed upon the end plate of the platen frame, so that by pinching one finger-piece toward the other, the line-spacing of the platen will be effected, and at the same time the operator will be given a grip upon the platen frame or carriage, for returning the same to begin a new line of writing.

These finger-pieces are located at the upper portion of the device, for ready access; and therefore the lever may be pivoted at the bottom of the end plate, and may be connected by an upwardly-extending link to a bell-crank mounted upon the platen axle, and having a pawl to engage the line-space wheel. These and the other devices connected with the line-space mechanism may be all arranged above the carriage tracks, even though the latter are placed very close to the bottom of the platen; thus securing the desideratum of compactness, which is essential in this class of machines.

The line-space regulator is simple, compact and effective, and is preferably controlled by the same spring which returns the line-space lever to normal position. The throw-off lever for disconnecting the spring-detent from the line-space ratchet wheel is

so formed as to be convenient of access and to clear the other parts of the mechanism, without sacrificing compactness.

Other features and advantages will hereinafter appear.

In the accompanying drawings,

Figure 1 is a part-sectional side elevation of the platen frame or carriage, etc., embodying the present improvements in line-spacing mechanism.

Fig. 2 is a part-sectional front elevation showing particularly the line-spacing bell-crank and connections.

Fig. 3 is a plan of the parts seen in Fig. 1.

Fig. 4 is a view similar to Fig. 2, but showing the line-space lever and connections with the bell-crank.

Fig. 5 is a plan showing the means for casting-off the spring-detent.

Fig. 6 is a view similar to Fig. 1, but omitting some of the parts for the sake of clearness.

The cylindrical platen 1 is mounted upon an axle 2 journaled in end plates 3 of a platen frame which may also constitute a letter-feeding carriage, the same having V-bars 4, 5, which, together with stationary tracks 6, 7, form raceways for carriage-guiding balls 8, 9.

Upon one end of the platen axle, within the platen frame, is fixed a line-space wheel 10 which is engaged by a roll detent 11 mounted between a pair of arms 12 pivoted upon a stud 13 projecting inwardly from an end plate 3 of the platen frame. A spring 14 is connected to a stud 15 which forms the arbor of the roll 11 and holds said roll in engagement with the line-space wheel.

The line-spacing is effected by a lever 16 pivoted at 17 upon the lower portion of the plate 3 and extending upwardly and having at its upper end a finger-piece 18 for pressing rearwardly; the end plate 3 of the platen frame being provided with an opposite coöperating finger-piece 19, which may be grasped by the finger while the finger-piece 18 is pressed rearwardly by the thumb, so that by an action of pinching 18 toward 19, the lever 16 is vibrated rearwardly, and the parts 18, 19 form a hand-hold for returning the carriage. This lever 16 has a

2
short rearwardly-extending platen-driving arm 20, which is connected by an upwardly-extending link 21 to a wrist 22 provided upon an arm 23 pivoted loosely upon the platen axle 2; said arm 23 being preferably upon the inner side of the plate 3, while the link 21 and lever 16, 20, are on the outside of said plate; and the link 21 extending from the arm 23 through an opening 24 in the 10 plate.

The arm 23 forms part of a bell-crank, the other arm of which is marked 25; said bell-crank being preferably formed of a single piece of sheet metal, which is folded at 26 15 near the fulcrum; the fold being open to give the bell-crank a suitable width of bearing on the axle 2, to reduce the liability of binding action. At its upper end the arm 25 carries a platen-driving pawl 27, normally 20 disengaged from the ratchet wheel 10, but automatically engaged therewith by means of a spring 28, as soon as the arm 25 begins to rock rearwardly. Thus the rearward movement of the line-spacing lever 16 pulls 25 down the link 21 and rocks the bell-crank 23, 25, causing the pawl 27 to drop into a tooth of the line-space wheel and then turn the wheel and platen. The line-space lever 16 is provided with a returning draw spring 30 29, connected at 30 to a stud upon the arm 20, and extending upwardly to a point of anchorage 31.

The platen turns until a toe 32 projecting from the pawl 27 engages a stop 33, where- 35 by the platen is arrested; the toe and stop coöoperating with the tooth 34 of the pawl to prevent overthrow of the platen, since any tendency of the ratchet tooth to force out the pawl tooth only causes the toe to press 40 more firmly against the stop 33; and the driving pressure upon the finger-piece 18 having the effect of forcing the pawl tooth 34 more firmly into the notch of the ratchet wheel, because of the coöperation of the toe 45 32 and the stop 33. The pawl 27 and the toe 32 form a bell-crank, the toe 32 extending toward the platen axle 2, and the pawl 27 extending around the ratchet wheel in advance of the pawl-carrying arm 25, where- 50 by these results are secured.

Upon the return of the parts to normal position, the spring 29 carries back the arm 25 and pawl 27 until the toe 32 engages with the wall 35 of the notch formed in the up- 55 per edge of the plate 3; and further return movement of the arm 25 causes the pawl to swing out of engagement with the ratchet wheel, because of the arrest of the toe 32.

The stop 33 is mounted upon an arm or 60 regulator 36, pivoted at 37 in the plate 3 and having a finger-piece 38, whereby it may be turned around its pivot to swing the stop 33 out of range of the toe 32, permitting said toe to engage the opposite wall 39 65 of the notch in the plate 3, at the conclusion

of a movement of the platen through two line-spaces. The spring 29 is connected to a pin 31 on said lever 36, and serves as a double-acting spring to hold said regulator either in its single-space position at Fig. 1 70 or in its double-space position at Fig. 6. Thus the single spring 29 serves both for turning the line-space lever and holding the line-space regulator in either position in which it is set. The toe 32 is bent out- 75 wardly, as indicated at 40, (Fig. 2), to enable it to project into the notch in the plate 3.

When it is desired to cast off the detent 11, the operator lifts a finger-piece 41 formed 80 upon a lever 42 pivoted at 43 on the lower rear portion of the plate 3, having a cam slot 44 to engage the projecting end 45 of the stud or arbor 15 upon which the detent roll 11 is mounted. By lifting this finger-piece 41, the stud 45 is cammed rearwardly, and the roll 11 swung out of engagement with the line-space wheel, so that the platen may be turned freely to any desired position. It will be seen that the lever 42 is 90 folded at 46 and has an arm 47 parallel with 42 at Fig. 5, and having the cam slot 44 as well as the pivot screw 43.

It will be observed that all of the parts are designed for lightness and compactness 95 as well as economy, these three features being of importance in portable typewriting machines, for which this invention is de-signed.

Variations may be resorted to within the 100 scope of the invention, and portions of the improvements may be used without others.

Having thus described my invention, I claim:

1. The combination with a platen, a platen 105 frame, and a line-space wheel, of a lever pivoted upon the platen frame and comprising an arm which extends upwardly and carries a finger-piece at its upper end, said lever also having a rearwardly-extending 110 arm, an up-and-down moving link extending upwardly from said rearwardly extending arm, a bell-crank mounted on the platen frame and comprising an up-and-down moving arm attached to said link, and a line-spacing pawl pivoted on the other arm of 115 said bell-crank.

2. The combination with a platen, a platen 120 frame, and a line-space wheel, of a lever pivoted upon the platen frame and extending upwardly and carrying a finger-piece at its upper end, said lever having a rearwardly-extending arm, a link extending upwardly from said arm, a bell-crank mounted 125 concentrically with the platen and comprising an arm attached to said link, and a line-spacing pawl pivoted on the other arm of 130 said bell-crank, said platen-frame comprising a plate upon the outer side of which said lever is pivoted, and said bell-crank ar-

ranged on the inner side of said plate and having a wrist extending through said plate to be engaged by said link.

3. The combination with a platen, a platen frame, and a line-space wheel, of a pivoted arm, a pawl upon said arm, a toe projecting from said pawl, a spring for returning said arm, said arm holding said toe against a fixture, to hold the pawl clear of the line-space wheel, and a stop in the path of said toe to be engaged thereby at the conclusion of the driving of the platen, to lock the pawl into the line-space wheel.

4. The combination with a platen, a platen frame, and a line-space wheel, of an arm pivoted to swing around the platen axis, a lever for driving said arm, a pawl upon said arm, a toe upon said pawl, a spring for returning said arm, said arm holding said toe against a fixture, to hold the pawl clear of the line-space wheel, and a stop engageable by said toe at the conclusion of the driving of the platen, to lock the pawl into the line-space wheel, said stop being adjustable out of the path of said toe, and a second stop being provided in the path of said toe to arrest the platen at the conclusion of a longer stroke thereof, and also to lock the pawl in engagement with the line-space wheel.

5. The combination with a platen, a platen frame, and a line-space wheel, of an arm pivoted to swing around the platen axis, a lever for driving said arm, a pawl upon said arm, a toe upon said pawl, a spring for returning said arm, said arm holding said toe against a fixture, to hold the pawl clear of the line-space wheel, a stop engageable by said toe at the conclusion of the driving of the platen, to lock the pawl into the line-space wheel, said stop being adjustable out of the path of said toe, a second stop being provided in the path of said toe to arrest the platen at the conclusion of a longer stroke thereof, and also to lock the pawl in engagement with the line-space wheel.

6. The combination with a platen, a platen frame, and a line-space wheel, of an arm pivoted upon the platen frame and extending upwardly and carrying a finger-piece at its upper end, said lever having a rearwardly-extending arm, a link extending upwardly from said arm, a bell-crank mounted concentrically with the platen and comprising an arm attached to said link, a line-spacing pawl pivoted on the other arm of said bell-crank, said frame comprising an end plate, a cam lever pivoted upon the outer side of said plate and comprising an arm 42 and a folded or offset portion 46, to enable 42 to clear the lever and link aforesaid, and a spring detent arm pivoted upon the inner side of said plate, and having a stud projecting through said plate to be cammed by said cam lever.

pivoted to swing around the platen axis, a lever for driving said arm, a pawl upon said arm, a toe upon said pawl, a spring for returning said arm, said arm holding said toe against a fixture, to hold the pawl clear of the line-space wheel, a stop engageable by said toe at the conclusion of the driving of the platen, to lock the pawl into the line-space wheel, said stop being adjustable out of the path of said toe, a second stop being provided in the path of said toe to arrest the platen at the conclusion of a longer stroke thereof, and also to lock the pawl in engagement with the line-space wheel, said movable stop being pivoted upon the platen frame, and a draw spring to hold said movable stop in either of its positions, said platen-driving lever being mounted upon the platen frame, and said draw spring being connected to said lever to return the same; a spring being provided for engaging said pawl with the line-space ratchet wheel.

7. The combination of a platen, a line-space wheel, mechanism for driving the line-space wheel, a returning spring for said driving mechanism, and a line-space regulator settable to different positions, said returning spring connected to said regulator to hold it in either position.

8. The combination with a platen, a platen frame, and a line-space wheel, of a lever pivoted upon the platen frame and extending upwardly and carrying a finger-piece at its upper end, said lever having a rearwardly-extending arm, a link extending upwardly from said arm, a bell-crank mounted concentrically with the platen and comprising an arm attached to said link, a line-spacing pawl pivoted on the other arm of said bell-crank, said frame comprising an end plate, a cam lever pivoted upon the outer side of said plate and comprising an arm 42 and a folded or offset portion 46, to enable 42 to clear the lever and link aforesaid, and a spring detent arm pivoted upon the inner side of said plate, and having a stud projecting through said plate to be cammed by said cam lever.

FRANCIS O. BURRIDGE,
*Executor of the last will and testament of
Lee S. Burridge, deceased.*
